Application December 7, 1938, Serial No. 244,443
In Great Britain December 8, 1937

26 Claims. (Cl. 40—28)

This invention relates to indicator devices in which one or more of a number of plates is selected and moved to indicating position.

The object of the invention is to provide a compact and practical device which is capable of providing, for instance, a choice of all the letters of the alphabet and the numerals 1—0.

According to the main feature of the invention an indicator device comprises a stack of closely-spaced parallel plates, means for selecting at least one of said plates, and means for moving a selected plate or plates out of the stack into indicating position.

The invention will be clearly understood from the following description of one embodiment shown in the accompanying drawings in which:

Fig. 1 is a side elevation of an electrically-controlled indicator device according to the invention;

Fig. 2 is a rear elevation of the indicator device;

Fig. 3 is a plan view of the device partially in section;

Fig. 4 is a detail view of changeover mechanism for the plate-selecting and moving equipment; while

Fig. 5 is the electrical control circuit for the indicator shown in Figs. 1—4.

Brief description of structure

The device comprises a stack of 72 plates, and both sides of each plate carry a quarter of a letter or figure. Groups of four spaced plates, e. g. Nos. 1, 19, 37, 55, each make up one complete letter or figure when their top sides are placed together, and a second complete letter or figure when the undersides are placed together. A total of $72 \div 4 \times 2 = 36$ letters and figures is thus obtained allowing for the 26 letters of the alphabet plus the ten figures.

The stack of plates 1, best shown in Fig. 3 and Fig. 1 is vertically movable, and each plate has on each side two pivot pins 5, 6, Fig. 3, which normally engage in horizontal slots 2 in side supports 3, 4 which are vertically movable as hereinafter explained. The long pivot pins 5 on each side pass through the supporting slots and engage in vertical slots in fixed uprights 12 which are supported by side plates 13 from fixed frame member 9 and which hold the plates 1 from lateral movement. The uprights 12 are cut away at four positions spaced so as to be always opposite a group of four plates carrying parts of the same letter or figure.

Uprights 15 positioned outside of the uprights 12 as well as outside of side plates 13 as best seen

in Fig. 3 carry lugs 14 which extend through openings in side plates 13 into the cut away portions of the uprights 12 and embrace the pivot pins 5 of the four plates in line with said cut away portions of uprights 12. The uprights 15 carry rollers 22 engaging horizontal channels 23, Fig. 1, in which the uprights 15 can be moved laterally by bell-cranks 16, 17 engaging slots 24 in the uprights. The bell-crank pairs 16, 17 are connected by links 18.

The front ends of the slotted supports 3, 4 are more widely spaced than the rest of the supports and are positioned behind horizontally slotted angle-members 34, Fig. 3, which are vertically movable under control of linkages 32, 33 at each side of the device, each lever 33 engaging a slot in the corresponding angle member 34. The actuation of these linkages is caused by shaft 31, the latter shaft being rocked by arm 31 which is moved by link 30.

It will be seen that when a group of plates is moved forward by uprights 15, their pivot pins 6 leave the slots in support 3 and engage the slots 27 in the angle members 34, while the pivot pins 5 remain in the slots in supports 3. Vertical movement of the member 34 upwardly or downwardly will turn the selected plates into a vertical position showing their top sides or undersides respectively.

The plate supports 3, 4 are mounted on a channel back plate 7 vertically slideable in rails 8 fixed to frame 9, the vertical movement being governed by an internally screwed boss 10 which is integral with back plate 7 and which extends through slots 9' of frame 9 to engage a vertical threaded spindle 11. Rotation of the spindle 11 thus moves the back plate 7 vertically in guides 8 in the frame 9 to raise or lower the side supports 3 and 4 so as to bring a desired group of plates in line with the lugs 14 on the laterally-movable supports 15.

The power for operating the various parts of the indicator device is furnished by spindle 46 driven by a motor M, which is only shown in Fig. 5, since it may be common to a number of indicator devices similar to the one herein described and illustrated. The reference character 47 in Fig. 2, represents the spindle of an adjacent indicator device and corresponds to the spindle 46 of the indicator device shown and described. As indicated in Fig. 5 the common motor M has multiplied starting circuits—one for each indicator device—so that this motor, and likewise all the spindles corresponding to spindle 46, will rotate whenever contacts 55 of any of 55

the common indicator devices are closed, i. e. whenever any of the indicator devices requires rotational power.

For making use of this rotational power of spindle 46 in the particular unit under consideration, a clutch 56 operable by solenoids 54 is provided as shown in Fig. 2. This clutch when operated drives gear 59, which in turn meshes with a gear 60 on the slideable clutch member 10' whose position is controlled by solenoid 69 as explained in more detail hereinafter. When slid to the right by solenoid 69, clutch 60' engages a cooperating member on shaft 43, thus driving this shaft to cause right hand rotation 15 of threaded spindle 11 through the reversible drive comprising gears 41, 42, 43' and reversing clutch 40. Normally, however, solenoid 69 is deenergized and clutch 60' is then positioned as shown so as to clutch with gear 61 which is in 20 engagement with a gear 62 fixed to spindle 21, thus driving this spindle 21. As shown in Figs. 1, 2 and 3, spindle 21 carries a contact making cam 63, a plate-tilting cam 25 for operating the linkage 30—33 and a crank and connecting rod assembly 20, 19 for operating the interconnected bell-cranks 16, 17, 18.

The cam 25 operates a rocker lever 26, an offset extension of which is pivoted at 29. The upper end of this rocker lever 26 is formed as 30 a slotted pivot plate 36 for link 30. The position of link 30 in the slotted plate 36 is controlled by a lever 35 which is operated by shaft 38 best shown in Figs. 2 and 4. As later described this shaft 38 is controlled by an arm 39 fixed to shaft 35 38 and moved by a vertical slotted link 37 carried by a bracket 10' fixed to the boss 10 of the vertically-movable stack assembly 3, 4, 7, 10. This linkage is arranged so that when the stack reaches its lowest and highest positions the lever 40 35 is thrown over by a snap action, which will be described later, from one position to another to control the movement of the linkages 30—33. When the link 30 is in the position shown in Fig. 1, cam 25 causes the left-hand end of levers 45 33 to move downwardly and so expose the tops of the selected plates. When link 30 is in its left-hand position, the levers 33 move upwardly to expose the undersides of the plates.

For controlling the position to which the stack 50 of plates is moved to select a letter or digit there is provided a single-motion wiper switch 44 comprising three bank contact levels and wipers 51, 52, 53. The location of this switch is best seen in Fig. 2 and its electrical connections are shown 55 in Fig. 5.

The levels 52, 53 are used as hereinafter described for marking the positions in which the stack 1 is to be stopped. For the present it is sufficient to state that the eighteen groups of 60 four plates each may be selected during downward movement of the stack via bank 52 and during upward movement of the stack via bank 51. The movement of the angle-members 34, Figs. 1 and 3 is so controlled that plates selected 65 during downward movement of the stack are turned to show their top sides while plates selected during upward movement of the stack are turned to show their undersides.

Various contact-spring pile-ups 45, 55, 57, 58, 70 75 and a relay 48, Fig. 5 are provided for controlling the indicator circuits shown in Fig. 5.

The details of the mechanism previously referred to which controls the rocking of shaft 38 can be most clearly seen in Fig. 4, which shows the shaft 38, lever 35 fixed thereto, and slotted

link 37 connected to bracket 10' which is carried by boss 10 for producing the rocking action of shaft 38 in substantially the same relative positions as these members are shown in Fig. 1. Referring more particularly to Fig. 4, it will be 5 noted that the slotted link 37 engages arm 39 fixed to shaft 38 in such manner as to actuate this arm to rock the shaft only at the extreme upper and lower limits of the stroke of the line 37. It will also be seen that the position of arm 37 is further controlled by a pair of cooperating wedge shaped members affixed respectively to arm 39 and to a stiff spring 69 so as to maintain arm 39 in the position to which it was last pushed or pulled by link 37 while at the same 10 time insuring that the movement of this arm 39 when it does take place is completed with a snap action. The rocking shaft 38 which is thus actuated by arm 39 under the joint control of link 37 and the snap action wedges carries not only lever 35 previously referred to, but also cam arm 85 for actuating contact spring pile-up 45. Additionally rocker shaft 38 also carries loosely journaled thereupon a reversing mechanism 71' which as seen in Figs. 2 and 4, has essentially the form of a loose sleeve bearing at one end means for shifting reversing clutch 40 and bearing at the other end a forked arm 71 by which the rocking of this reversing mechanism 71' is controlled. 20

The arm 39 has a lost-motion connection with a forked arm 71, Figs. 2 and 4, which is journaled on shaft 38 and an intermediate arm 71'' of mechanism 71' also carries a wedge cooperating with a wedge on a spring 70 weaker than spring 69. The forked arm 71 controls the reversing clutch 40, and is not moved until the lever 39 has moved so far that spring 69 takes control and moves both lever 39 and arm 71 by snap action to their reverse positions. Thus reversal 40 of the drive of lead screw 11 does not take place until the vertically-movable stack assembly 3, 4, 7, 10 which by means of bracket 10' carries slotted link 37 has completed its stroke. 30

General sequence of operation 45

The control of the indicator is intended to be effected by placing a marking potential such as ground potential upon one of the contacts in bank 51 or bank 52 of switch 24, 44, the contact thus marked determining the character which will be displayed. Whenever it is desired to change the displayed character the marking ground is removed from the terminal on which it previously existed and is applied to the new terminal corresponding to the new character desired. The principal steps in the sequence of operation for effecting such a change of the character displayed is as follows:

Normally a group of plates will be in indicating position. When the marking on the switch is changed, shaft 21 is given a half revolution to withdraw the plates into the stack, the stack is then moved downwardly or upwardly by rotation of lead screw 11 according to the direction in which the stack last moved either until it reaches a marked contact, or reaches the bottom or top of its travel. In the latter case the direction of movement will be automatically reversed and the search for the marked position continued. Whenever such reversal occurs cam arm 85 also shifts contacts 45 so that the switch level corresponding to the new direction of travel of the stack of plates 1 will be searched over. 70

Finally when the marked group of plates is 75

selected screw spindle 11 is stopped and shaft 21 is given another half-revolution to move the selected group of plates to indicating position.

Detailed description of operation

In the set position of the indicator, marking ground potential on the bank 52 or 51 passes via contacts 45 to hold relay 48 energised, opening its contacts 481, 482 so that the indicator 10 remains at rest.

When marking ground potential is taken off the contact over which relay 48 is energised, the relay releases and solenoid 54 is energised via 481. As will be seen from Fig. 2, solenoid 54 15 closes clutch 56 to drive gear wheels 59, 60 and at the same time closes contacts 55 to start the motor M, Fig. 5, to drive shaft 46.

Gears 59, 60, 61, 62 drive shaft 21 so that the crank linkages 20, 19, 18, 17, 16 withdraw the 20 supports 15 rearwardly, Fig. 1, while the cam 25 rocks lever 26 so that its slotted plate portion 36 pulls or pushes link 30. This motion of line 30 is transmitted through arm 31, shaft 31' and linkages 26, 30, 31, 32, 33 to shift uprights 34 25 for turning the plates into horizontal position.

When the indicator is set, the recess shown at the bottom of the cam 63 in Fig. 1 is opposite the contact-operating roller so that contacts 57, 58 are both open. When shaft 21 begins to rotate, contact 57 but not 58 is closed and a circuit is formed via off-normal bank 53, Fig. 5, to hold solenoid 54 energised until a complete half-revolution has been made even if relay 48 reoperates. This prevents stoppage with the indicator 35 in a partly-set condition.

When the shaft 21 has completed the half-revolution, contacts 58 are also closed as shown in Fig. 1, and solenoid 64 is energized. Solenoid 68 operates clutch 60', disengaging gear-wheels 61, 62, and engaging the shaft 43 which drives the lead screw 11. The solenoid also operates arm 65 to engage a slotted wheel 66 on shaft 21. If shaft 21 has not completed its rotation arm 65 cannot enter the slot and changeover of the clutch 60' is prevented. At the same time an arm 67 which is in engagement with one of two diametrically opposite radial slots in a disc 68 on shaft 43 is withdrawn to allow shaft 43 to rotate. Contacts 75, Figs. 1 and 5, are controlled 45 by a roller which normally engages a recess in the face of disc 68 so that the contacts are normally open when the shaft 43 rotates, contacts 75 are closed to hold the circuit of solenoid 69 closed during each revolution of shaft 43.

The lead screw 11 moves the stack downwardly for instance and at the same time through worm gears 72, 73 rotates the switch 44. Let us assume that the new marked position is not reached before the stack reaches the bottom of its stroke. As it approaches the bottom of its stroke, the upper end of the slot in link 37 impinges on roller 76 in the end of arm 39 of lever 35 arm 39 therefore rocks the shaft 38 so that lever 35 changes over the position of link 30 in the slotted plate 55 36 while cam arm 85 shifts contacts 45 to transfer the marker control from switch level 52 to level 51. The first part of this rocking movement also causes the wedges on arm 39 and spring 69 to force spring 69 to the right until the points of the wedges pass one another when the arm 39 completes its stroke by snap action as previously described. During the last part of this motion which thus takes place with the snap action, reversing mechanism 71' is carried along with arm 39 because the lost motion be-

tween 39 and 71 has now been taken up. The reversing mechanism thus moves reversing clutch 40 to reverse the drive of screw 11.

When the operative wiper 51 or 52 finds a grounded contact, relay 48 energizes (see Fig. 5) 5 and opens contacts 482 so that on completion of the revolution of shaft 43, solenoid 69 is deenergized. Clutch 60' will thereupon restore to normal position to drive shaft 21 again when the shaft 43 has reached the position in which arm 10 67 can engage the slotted disc 68.

Although relay 48 is now operated, solenoid 54 is still energized via off normal wiper and bank 53 and contacts 57 of cam 63, Figs. 1 and 5, which is standing in the position shown in Fig. 1. The motor M therefore continues energized over contacts 55. When the shaft 21 starts to move contacts 58 are opened to prevent any possibility of solenoid 69 reoperating but contacts 57 remain energized until the shaft 21 completes a half revolution and the contact roller enters the recess in cam 63 and allows contacts 57 to open.

During this half-revolution the crank 20, link 19 and bell-cranks 16, 17 move the supports 15 25 and the selected plates forward and when the rocker pivots 6 enter the slots 27 the upward or downward movement of the angle-members 34 dependent on the position of link 30 turns the selected plates to expose their undersides or top 30 sides respectively to view.

It will be noted that the off-normal level 53 of the marker switch has one contact disconnected. This position of the switch is provided for controlling a blank indication. If lead 71 35 to the corresponding contact in level 52 is grounded, relay 48 is energized when the position is reached and immediately, both circuits for solenoid 54 are opened, at 481 and by wiper 53 respectively. Solenoids 69 and 54 therefore release together so that shaft 21 does not make its half-revolution to move a selected group of plates into indicating position and no indication is given. In this case when the marking on the banks of switch 44 is changed, relay 48 releases, 45 but as contacts 57, 58 are both energized, both solenoids 54, 69 energize together. Shaft 21 is not given a preliminary half revolution but the stack 1 is immediately moved by lead screw 11 to position the group of plates required by the 50 new marking on the switch.

What is claimed is:

1. An indicator device comprising a stack of closely-spaced parallel plates, means for selecting any desired one of said plates independent 55 of its position in said stack and means for moving said selected plate out of the stack into an indicating position at right angles to the plane of the plates in the stack whereby said plates may be moved into indicating position in any 60 desired order independent of their succession in said stack.

2. An indicator device comprising a stack of closely-spaced parallel plates, electrically controlled, means for selecting any desired one of 65 said plates independent of its position in said stack and means for moving said selected plate out of the stack into an indicating position at right angles to the plane of the plates in the stack whereby said plates may be moved into 70 indicating position in any desired order independent of their succession in said stack.

3. An indicator device comprising a stack of closely-spaced parallel plates, means for selecting any desired one of said plates independent 75

- of its position in said stack, means for shifting the stack at right angles to the plane of the plates to bring the selected plate in a predetermined position, and means for moving said selected plate out of the stack to an indicating position at right angles to the plane of the plates in the stack whereby said plates may be moved into indicating position in any desired order independent of their succession in said stack.
10. An indicator device comprising a stack of closely-spaced parallel plates, electrically-controlled, means for selecting any desired one of said plates independent of its position in said stack, means for shifting the stack at right angles to the plane of the plates to bring the selected plate in a predetermined position, and means for moving said selected plate out of the stack to an indicating position at right angles to the plane of the plates in the stack whereby said plates may be moved into indicating position in any desired order independent of their succession in said stack.
15. An indicator device comprising a stack of closely-spaced parallel plates, means for selecting any desired one of said plates independent of its position in said stack, means for moving said selected plate out of the stack to an indicating position at right angles to the plane of the plates in the stack, and means for selectively turning the selected plate in one direction or another so that either one of its faces can be exhibited in the indicating position whereby said plates may be moved into indicating position in any desired order independent of their succession in said stack.
20. An indicator device comprising a stack of closely-spaced parallel plates, electrically-controlled, means for selecting any desired one of said plates independent of its position in said stack, means for moving said selected plate out of the stack to an indicating position at right angles to the plane of the plates in the stack, and means for turning the selected plate in one direction or another so that either one of its faces can be exhibited in the indicating position whereby said plates may be moved into indicating position in any desired order independent of their succession in said stack.
25. An indicator device as claimed in claim 12 and comprising means for selectively turning each plate of the selected set in one direction or another so that either one of its faces can be exhibited in the indicating position.
30. An indicator device as claimed in claim 5, and in which the means for selecting a plate comprises an electrical selector device arranged to be operated in step with movement of the stack to test in turn different electrical marking circuits, and test means arranged to be operated over one of said marking circuits to stop movement of the stack.
35. An indicator device as claimed in claim 5, and comprising a common drive and clutches for clutching in turn to the common drive the means for moving the stack and the means for moving the selected plate out of the stack into indicating position.
40. An indicator device as claimed in claim 8 and comprising a first rotatable spindle for moving the stack, a second rotatable spindle carrying means for moving the plates out of the stack and for turning each selected plate into indicating position, driving means for the shafts, and clutch means for connecting the drive to the two shafts in turn.
45. An indicator device as claimed in claim 8, and comprising driving means for the stack arranged to move the stack in opposite directions in turn between extreme positions, and control means arranged to cause said selected plate to be turned to exhibit one face in response to the occurrence of the selection during movement of the stack in one direction and to cause said selected plate to be turned to exhibit the other face in response to the occurrence of the selection during movement of the stack in the opposite direction.
50. An indicator device comprising a plurality of sets of plates disposed in closely spaced parallel arrangement to form a stack, means for selecting any desired one of said sets of plates independent of the relative position of said set of plates in said stack, means for shifting said stack at right angles to the plane of the plates to bring the selected set of plates to a predetermined set of positions, and means for moving the plates of the selected set out of the stack into an indicating position at right angles to the plane of the plates in stack whereby said sets of plates may be moved into indicating position in any desired order independent of the sequence of said sets of plates in said stack.
55. An indicator device comprising a stack of closely-spaced parallel plates each bearing matter to be displayed when a group of one or more of the plates is brought into an indicating position which is at right angles to the plane of the plates in the stack, means for selecting any one of the groups of plates for display regardless of the identity of the last group displayed, and means for moving the selected group only, out of the stack into the indicating position.
60. An indicator device comprising a stack of closely-spaced parallel plates each bearing matter to be displayed when a group of one or more of the plates is brought into an indicating position which is at right angles to the plane of the plates in the stack, means for selecting any one of the groups of plates for display regardless of the identity of the last group displayed, means for shifting the stack at right angles to the plane of the plates to bring the selected group into a predetermined position, and means for moving the selected group from that predetermined position out of the stack into the indicating position.
65. An indicator device comprising a stack of closely-spaced parallel plates each bearing matter to be displayed when a group of one or more of the plates is brought into an indicating position which is at right angles to the plane of the plates in the stack, means for selecting any one of the groups of plates for display regardless of the identity of the last group displayed, means for moving the selected group only, out of the stack into the indicating position, and means for turning the selected group in one direction or another so that either one of its faces can be displayed in the indicating position.
70. An indicator device comprising a stack of closely-spaced parallel plates each bearing matter to be displayed when a group of one or more of the plates is brought into an indicating position which is at right angles to the plane of the plates in the stack, means for selecting any one of the groups of plates for display regardless of the identity of the last group displayed, means for shifting the stack at right angles to the plane of the plates to bring the selected group into a predetermined position, means for moving the

selected group from that predetermined position out of the stack into the indicating position, and means for turning the selected group in one direction or another so that either one of its faces can be displayed in the indicating position.

17. An indicator device as claimed in claim 5, comprising driving means for the stack arranged to move the stack in opposite directions in turn between extreme positions, control means arranged to cause a selected plate or plates to be turned to exhibit one face if selected during movement of the stack in one direction and to be turned to exhibit the other face if selected during movement of the stack in the opposite direction, and means operable by the stack in its extreme positions to change the setting of said control means.

18. An indicator device as claimed in claim 5, comprising driving means for the stack arranged to move the stack in opposite directions in turn between extreme positions, control means arranged to cause a selected plate or plates to be turned to exhibit one face if selected during movement of the stack in one direction and to be turned to exhibit the other face if selected during movement of the stack in the opposite direction, and means operable by the stack in its extreme positions to change the setting of said control means, and also controlling reversing equipment for the driving means for the stack.

19. An indicator device as claimed in claim 8, and comprising a first rotatable spindle for moving the stack, a second rotatable spindle carrying means for moving the plates out of the stack and for turning each selected plate into indicating position, driving means for the spindles, clutch means for connecting the drive to the two spindles in turn, and positive locking means which prevent change over of the drive from one spindle to another unless the spindles are in a predetermined position.

20. An indicator device comprising a stack of closely-spaced parallel plates each bearing matter to be displayed when a group of one or more of the plates is brought into an indicating position, means for selecting any one of the groups of plates for display, means for shifting the stack as a whole in a direction at right angles to the plane of the plates to bring the selected group into a predetermined position, and means for moving the selected group from that predetermined position out of the stack into the indicating position.

21. An indicator device comprising a stack of closely-spaced parallel plates each bearing matter to be displayed when a group of one or more of the plates is brought into an indicating position, means for selecting any one of the groups of plates for display regardless of its position in the stack, and power-driven means for moving the selected group out of the stack into the indicating position.

22. An indicator device comprising a stack of closely-spaced parallel plates each bearing mat-

ter to be displayed when a group of one or more of the plates is brought into an indicating position, means for selecting any one of the groups of plates for display regardless of its position in the stack, power-driven means for shifting the stack in a direction at right-angles to the plane of the plates to bring the selected group into a predetermined position, and power-driven means for moving the selected group from that predetermined position out of the stack into the indicating position.

23. An indicator device comprising a stack of closely-spaced parallel plates each bearing matter to be displayed when a group of one or more of the plates is brought into an indicating position which is at right angles to the plane of the plates in the stack, means for selecting any one of the groups of plates for display regardless of its position in the stack, and means for moving the selected group only, out of the stack into the indicating position.

24. An indicator device comprising a stack of closely-spaced parallel plates each bearing matter to be displayed when a group of one or more of the plates is brought into an indicating position which is at right angles to the plane of the plates in the stack, means for selecting any one of the groups of plates for display regardless of its position in the stack, means for shifting the stack at right angles to the plane of the plates to bring the selected group into a predetermined position, and means for moving the selected group from that predetermined position out of the stack into the indicating position.

25. An indicator device comprising a stack of closely-spaced parallel plates each bearing matter to be displayed when a group of one or more of the plates is brought into an indicating position which is at right angles to the plane of the plates in the stack, means for selecting any one of the groups of plates for display regardless of its position in the stack, means for moving the selected group only, out of the stack into the indicating position, and means for turning the selected group in one direction or another so that either one of its faces can be displayed in the indicating position.

26. An indicator device comprising a stack of closely-spaced parallel plates each bearing matter to be displayed when a group of one or more of the plates is brought into an indicating position which is at right angles to the plane of the plates in the stack, means for selecting any one of the groups of plates for display regardless of its position in the stack, means for shifting the stack at right angles to the plane of the plates to bring the selected group into a predetermined position, means for moving the selected group from that predetermined position out of the stack into the indicating position, and means for turning the selected group in one direction or another so that either one of its faces can be displayed in the indicating position.

JOHN HANDLEY.
